UNITED STATES PATENT OFFICE.

FREDERICK S. McCULLOUGH, OF CLEVELAND, OHIO, ASSIGNOR TO GLENN L. MARTIN,
OF CLEVELAND, OHIO.

RADIOTELEGRAPHY.

Application filed August 2, 1919. Serial No. 314,954.

To all whom it may concern:

Be it known that I, FREDERICK S. McCULLOUGH, a citizen of the United States, resident of Cleveland, county of Cuyahoga, and State of Ohio, have invented new and useful Improvements in Radiotelegraphy, of which the following is a specification, the principle of the invention being herein explained and the best mode in which I have 10 contemplated applying that principle, so as to distinguish it from other inventions.

My invention relates to systems of radio telegraphy, and more particularly to systems for determining the direction of distant transmitting stations. It also relates 15 to systems for detecting the incoming electromagnetic waves.

In the radio directional systems hitherto used, there have been employed large antennae arranged in certain shapes and directions, and also loops or coils of wire, these coils generally having a number of turns wound on a square frame with the sides several feet or several yards in length.

20 While directional loops of such size may answer for permanent land stations, it can be readily seen that there are grave objections to them for portable stations such as those on a small boat, and more particularly on aircraft. For the latter it is essential to have the apparatus in as compact form as possible, and by my system I provide means of small size which will satisfactorily determine the direction of transmitting radio stations. Together with my direction finding, 25 I provide for the detection of the incoming electrical oscillations.

The annexed drawings and the following description set forth in detail certain means 30 embodying my invention, the disclosed means, however, constituting but one of the various mechanical forms in which the principle of the invention may be employed.

In the drawings, which are largely dia- 35 grammatic, Figure 1 shows one form of my invention, with one of the elements shown in cross-section, the section being taken on the line C—D, in Figure 2.

Figure 2 is a view, partly in section, showing 40 some of the elements of my system, the cross-section being taken on the line A—B, in Figure 1.

Figure 2^a shows a modified form of my flat coil in the form of a circular spiral.

Figure 2^b shows a section of the ribbon 55 conductor of my flat spiral coil, on an enlarged scale.

Figure 3 is a modified form of my system, with means for indicating visually the received signals. 60

Figure 4 is another modification of my system, with other means for indicating visually the strength of the received signals.

Figure 5 shows another modification of my system. 65

Figure 6 shows another modification of my system with the flat spiral coil enclosed in an evacuated tube.

In Figure 1, 1 is a vacuum bulb or tube; 2 is a filament which may be heated; 3 is a 70 plate of conducting material which is here shown disc-shaped, but may have any other suitable shape; 4 is a battery for heating filament 2, and 5 is a variable resistance for regulating the current therein. 6 is a battery for energizing the circuit containing the plate 3, the filament 2 and an indicating means 7 which is here shown as a telephone, but may be any other suitable indicating means; 8 is a section of a flat coil made of 75 a conducting ribbon wound in a square spiral with the adjacent turns placed edge to edge. 9 is a variable inductance and 10 a variable condenser in the circuit connecting the flat coil 8 and the filament 2. 11 is a ring to 80 which the coil 8 is secured, and which slips over the tube 1, along which it may move. Suitable flexible connections with coil 8, or sliding contacts, are provided to permit of its motion. This ring 11 is preferably of 85 conducting material, in which case the inner turn of the spiral 8 is electrically connected with it.

In Figure 2, which is a section taken on the line A—B, looking in the direction of 90 the arrow, 1 is the vacuum tube; 2 is a cross-section of a filament; 3 is an end view of the plate; 11 is the ring about the tube to which the spiral coil 8 is attached; and 42 is a frame attached to the ring 11 so that 95 the coil 8 may be more conveniently secured and supported. 41, 41, are blocks or pieces of insulating material for keeping the turns of the spiral separated from each other.

In Figure 2^a, 1 is the tube; 2 is a cross-section of the filament; 3 is the flat plate; 11 is the ring about the tube; and 12 is the 100 flat coil wound in the form of a circular

spiral. 41, 41, are blocks or pieces of insulating material for keeping the turns of the spiral separated from each other.

In Figure 2^b, the section of the ribbon 5 conductor of my flat spiral coil is shown on an enlarged scale. In some embodiments of my invention I have made this ribbon about .005 inch thick, and about $\frac{1}{16}$ or $\frac{3}{32}$ inch wide, but I do not confine myself to these 10 sizes and proportions. I may also make my coil of as many turns as found most suitable for a given case. In these ways I can vary the capacitance and inductance of my coils, to suit the wave lengths and other conditions 15 of any case. In order to get the greatest directive effect in the coil, it is advisable to have the greater part of the inductance and capacitance of its circuit in the coil itself.

In Figure 3, 2 is a filament which may 20 be heated by current from the battery 4, 5 being a variable resistance for regulating the current in the filament. 8 is a flat spiral coil similar to the one already described; 11 is a ring or band fitting on the vacuum tube 25 13, along which it may move. Suitable flexible connections or sliding contacts are provided, to permit of this motion. 14 is a small flat spiral coil of a few turns contained within the tube 13 and electrically 30 connected with the flat spiral coil 8, as shown. Coil 14 is also connected to the filament 2 through the variable inductance 9 and variable condenser 10. 15 is a flat coil in the form of a circular spiral having more 35 turns than has coil 14. Coil 15 is also located within the tube 13 and is connected with the flat coil 8 through the variable inductance 16 and variable condenser 17. It is also connected with a cathode-ray tube 18 40 which serves as a visual indicator. 19 is an induction or spark coil; 20 is an anode and 21 a cathode within the cathode-ray tube and connected to the terminals of the spark coil. 22 is a diaphragm in the cathode-ray 45 tube, having a small opening which permits a beam or pencil of cathode rays to pass through. 23 and 24 are electrodes in the cathode-ray tube and connected with the circuit which also includes plate 15, the filament 2 and the battery 6. 25 and 26 are 50 positions assumed by the beam of cathode rays when under the influence of the electrodes 23 and 24. 27 is a screen, which may be of mica or some other suitable material, 55 on which the beam of cathode rays impinges making a spot of light when the beam is at rest and a line of light when it is in rapid motion.

In Figure 4, 13 is a vacuum tube; 28 is 60 a filament contained in the tube which can be heated by the battery 4, the current in this local circuit being regulated by the variable resistance 5. 30 is a coil in the tube and here shown extending nearly through- 65 out the length of the tube, but this coil may

have any suitable length. This coil 30 is connected with the filament 28 through the variable inductance 9 and variable condenser 10. Coil 30 is also connected with another coil 31 wound outside of the tube 13 70 on a ring or band 32 which fits over the tube and can be moved along it. A cylindrical covering, 43, may surround coil 31. Coil 31 is also connected with the flat spiral coil 8, which is similar to the coils 8 shown in the 75 previous figures. Coil 8 is attached to a ring 33 which fits over the coil 31 and is movable along the latter and also along the tube 13. Suitable flexible connections or sliding contacts are made with coils 31 and 80 8, in order to permit of their motion. 29 is another coil contained within the tube 13 and wound outside the coil 30, and here shown extending nearly throughout the 85 length of the tube, but this coil may have 90 any suitable length. Coil 29 is connected with coil 8 through the variable inductance 16 and the variable condenser 17, and is also connected with the filament 28. In the latter circuit are included the battery 6 and the galvanometer 34. The galvanometer 34, 95 which may be of any suitable kind, serves to indicate visually the strength of the signals received by the system, but instead of a galvanometer there may be used any other suitable visual indicator, or any other suitable means for indicating or recording signals. 95

In Figure 5, 35 is a vacuum tube; 28 is a filament contained therein, this filament being heated by a battery 4, and the current therethrough being regulated by the variable resistance 5. 29 is a coil within the tube 35, and here shown extending nearly throughout the length thereof, but it may have another suitable length; 36 is a coil wound outside the tube, and preferably extending the length thereof, but it may have any other suitable length. It is movable with respect to the tube 35, and is connected with the coil 29 through the variable condenser 17, and with the filament 28 through the variable inductance 9 and variable condenser 10. Suitable flexible connections or sliding contacts are provided to permit of such motion. The coil 29 is connected with the filament 28, the circuit including also the variable battery 6 and the indicating means 7, which is here shown as a telephone, but which may be any other suitable indicating means, either audible or visual. 110 115 120

In Figure 6, 37 is an evacuated tube, which is shaped so as to contain the flat spiral coil 8. 28 is a filament; 29 is a coil, preferably extending through the greater part of the length of the tube; 30 is another 125 coil between the filament and coil 29, and also preferably extending through most of the tube. Coil 30 is connected with one end of the flat spiral coil within the tube. 4 is a battery for heating the filament 28, and 130

5 is a variable resistance for regulating the strength of the current therein. 9 is a variable inductance and 10 a variable condenser between the coil 30 and filament 28. 16 is 5 a variable inductance and 17 a variable condenser between the coil 29 and the flat spiral coil 8. 6 is a variable battery for energizing the circuit comprising coil 29, filament 28 and galvanometer 34. Galvanometer 34 10 may be of any suitable kind, and will indicate visually the strength of the received signals, but instead of the galvanometer, any other means for indicating these signals visually or audibly may be used. The flat 15 spiral coil 8 may be attached to a ring or frame 39, and supported in the tube by the wires or rods 38, 38, and 40, 40; but any other suitable means of supporting and securing this coil may be employed. This flat 20 spiral may be either circular, square or rectangular in shape, as found most convenient.

The flat spiral coils which have been described above are preferably composed of a 25 thin ribbon shaped conductor, the cross-section of which is rectangular or oblong in shape. They may have any convenient number of turns and their dimensions over all may be a foot or less, although in some 30 cases they may be larger than this. When enclosed in an evacuated tube, it will be convenient to have the greatest dimension of the coil less than a foot. This flat spiral coil with the ribbon-shaped conductor is 35 sharply directive and enables me to provide a sensitive and efficient direction finder in a small and compact form. The square shape has mechanical advantages in construction and support, but a circular shape 40 may also be used. Where necessary the turns of the coil may be kept separated by means of pieces of insulating material and where advisable an insulated framework 45 may be employed to support the coil and preserve its shape. In one method of construction I wind my spiral on a flat surface, then dip it in an insulating enamel bath, heat it in an oven, and then place it between two sheets or blocks of insulating material, such as bakelite. In this way the 50 turns of the spiral are insulated from each other, the spiral is insulated from outside conductors, and the spiral is supported and its shape preserved. In this way it is also 55 protected from dampness, corrosion, or other atmospheric influences. When used outside of the tube, the coil may be moved along the tube into the position found most advantageous.

60 In the arrangement shown in Figure 1, it has been found that the best position for coil 8 is that in which its plane lies between the end of filament 2 and plate 3. In this position it is probable that its field will be strongest in the space between the filament

2 and the plate 3, and so will have the greatest influence in modifying the flow of electrons between filament 2 and plate 3.

In the arrangement shown in Figure 3, coils 14 and 15 and the flat spiral coil 8 are 70 shown in perspective, for the sake of clearness. Coil 14 should preferably have fewer turns than coil 15. Coil 14 should preferably be in the same plane with coil 8 and both these coils and coil 15 should be parallel to each other. These coils should also preferably all be wound in the same sense. In this arrangement the principal directional effect is probably due to coil 8, although coils 14 and 15 75 will assist. The detecting function with this arrangement is largely due to the combined action within the tube of filament 2 and coils 14 and 15, assisted to some extent by coil 8 and by the other apparatus outside of the tube. The strength of the signals is indicated by the aid of a cathode-ray tube 18, the action of which has been fully explained in my co-pending application Serial No. 313,161, filed July 2, 1919. It 80 will be sufficient to say here that the variations in the electrification of the electrodes 23 and 24, due to the incoming electromagnetic waves, as modified by the receiving apparatus, cause the beam of cathode rays 85 25 and 26 to move from its normal position and to trace a line of light on the screen 27. The length of this line will indicate the strength of the received signals.

In the arrangement shown in Figure 4, the directional effect is obtained by all the coils, both those inside the tube and those outside the tube. These coils should preferably be parallel to each other and all wound in the same sense. The inductance of the system may be varied by the coil 31, which can slide outside of the tube. The wave-detecting function is largely due to the filament and coils within the tube. In this figure the galvanometer is shown as the means for indicating the strength of the received signals. This galvanometer may have a reed or other movable part which can be tuned to the spark or group frequency of the transmitting station, but it may be of any other 115 suitable kind, and instead of a galvanometer, I may employ a cathode-ray tube or any other suitable visual or audible means of indicating the strength of the received signals.

In the arrangement shown in Figure 5, the directive effect is secured by both coils, and the detecting effect is partly due to the field created in the space within the tube by the coil 36, which is wound outside of the tube and closely adjacent thereto. The inductance of the system can be varied by sliding coil 36 along the tube.

In the arrangement shown in Figure 6, the directive effect is secured by the action

of all the coils, which should be parallel to each other and which should preferably be wound in the same sense. The detecting function is performed by the combined action of all the elements within the tube, and is probably principally due to the filament 28 and coils 30 and 29. The flat spiral coil 8 may be supported as shown, or where advisable, it may have an insulated frame-work to help support it and preserve its shape and to keep adjacent turns from touching, or it may be held between two sheets or blocks of insulating material.

I find that the maximum effect is produced by the incoming electromagnetic waves when the planes of my coils are parallel to the direction of the transmitting station, or, in other words, when the axes of the coils are perpendicular to the line joining the transmitting and receiving stations. I therefore turn my tubes and my coils until the maximum effect is observed on my visual or audible or other indicating means, when the planes of my coils will point toward the transmitting station. Where my coils do not lie in a plane, as for instance, when they are wound in helical form, the direction is the average direction of the individual turns, or, more exactly, the direction perpendicular to the axis of the coil. Sometimes it is more convenient to determine the position for minimum effect, which is at right angles to the position for maximum effect.

35. I may combine different units of my system so as to indicate simultaneously the positions for maximum and minimum effect of the received signals. I may also employ these units so as to show simultaneously the direction of two or more distant transmitting stations. I may also combine different elements so as to secure amplifying effects for the received radiant energy.

In the system shown in this application, 45 and in all other modifications coming within the scope of my invention, I may tune my circuits to the wave length of the transmitting station or stations; and other parts of my receiving apparatus such, for instance, 50 as the galvanometer, may be tuned to the spark or group frequency of the transmitting station or stations. In this manner I can secure highly selective effects.

In all the embodiments of my system, the

size or dimensions and forms of my elements 65 and the electrical quantities involved are so chosen as to secure the best results in each case. In general, I do not limit myself to the exact constructions and arrangements shown in this specification, but any suitable 60 means coming within the scope of my invention may be employed.

What I claim and desire to secure by Letters Patent is:

1. In a radio system, in combination, a 85 vacuum tube, a filament and a plurality of coils contained therein, and a coil surrounding said tube, the axes of all said coils being parallel to each other, said coils being connected conductively. 70

2. In a radio system, in combination, a vacuum tube containing a filament and a plurality of coils, and a flat spiral coil about said tube having its plane perpendicular to the axes of said coils within the tube, said 75 coils being connected conductively.

3. In a radio system, a receiving circuit comprising a vacuum tube, a filament, a plate element within said tube, and a directional receiving element surrounding said 80 tube.

4. In a radio system, in combination, a vacuum tube containing a filament and a plate, and a flat spiral coil surrounding said tube, having its plane perpendicular to the 85 axis of said tube.

5. In a radio system, in combination, a vacuum tube, a filament, a coil of wire, a second coil of wire, said coils being parallel to each other and together with the filament 90 being contained in said tube, and a ribbon-shaped conductor wound in a flat spiral outside of the tube and adjacent thereto, and with its plane parallel to said coils inside the tube. 95

6. In a radio system, the combination of a vacuum tube, a filament, a plate member, and a third member comprising a coil within said tube, a coil outside said tube and partly surrounding the tube, and a flat 100 spiral coil outside said tube, said three coils being connected conductively.

7. In a radio system, in combination, a vacuum tube, a filament, coils within said tube, and movable coils surrounding said 105 tube, said coils being connected conductively.

Signed by me, this 29th day of July, 1919.
FREDERICK S. McCULLOUGH.
